UNITED STATES PATENT OFFICE

2,690,189

CONTROL APPARATUS FOR FUEL BURNING APPLIANCES

Harold W. Rice, Los Angeles, Calif., assignor to
Robertshaw-Fulton Controls Company, Greens-
burg, Pa., a corporation of Delaware

Application January 13, 1951, Serial No. 205,864

6 Claims. (Cl. 137—65)

1

This invention relates to control apparatus for fuel burning appliances and, more particularly, to a combination automatic pilot and electrically operated valve.

In many fuel burning appliances, an automatic pilot valve and a separate solenoid valve are placed in series in the fuel supply line. The automatic pilot valve prevents the escape of unburned fuel in the usual manner while the solenoid valve serves either as a time or temperature control or over-temperature shut-off and the like being in each case under the control of an appropriate switch. Such an arrangement involves the cost of two separate control valves. Another disadvantage is the resultant pressure drop through two valves.

The present invention has for an object the reduction of initial cost and upkeep in fuel burning appliances. At the same time, a reduction in the pressure drop through the system is also obtained. In the described embodiment of the invention, a single control valve is utilized to achieve the foregoing objects and is controlled individually by thermally responsive means and an electrical relay through a lever device which may take any one of several forms.

Thus, one embodiment of such a control apparatus for fuel burning appliances having main and pilot burners provides a control valve having open and closed positions for controlling the fuel supply to the main burner and being biased to one of said positions, a lever device operably associated with said control valve, means responsive to a flame at the pilot burner and effective for operating said lever device for moving said control valve to the other said position, electrically operated means for operating said lever device to effect movement of said control valve under said bias when said flame responsive means is effective and switch means operable for controlling the energization of said electrically operable means.

Such a combination control may be used on a fuel burning appliance, such as a gas range, for the usual automatic pilot and in connection with a clock control switch for automatic time control of the oven. On a space heater, this combination device would serve as the automatic pilot and, in connection with a thermostatic switch, would function as a thermostatic valve. These and other embodiments of the invention will be apparent to those skilled in the art as the following description proceeds. Moreover, other objects and advantages of the invention will become apparent from the following description

2

taken in connection with the accompanying drawings wherein:

Fig. 1 is a schematic view of a fuel burning appliance having the invention applied thereto;

Fig. 2 is an enlarged elevation, partly in section, of the control apparatus shown in Fig. 1;

Fig. 3 is a plan view of the control apparatus shown in Fig. 2;

Fig. 4 is an elevation, partly in section, of a modified form of control apparatus and;

Fig. 5 is an elevation, partly in section, of a further modified form of control apparatus.

Referring more particularly to Fig. 1, a fuel burner installation is shown as comprising a main burner 10 receiving a supply of fuel from a manifold 12 by way of a main fuel pipe 14. Interposed in the main fuel pipe 14 is a series arrangement of a main shut-off cock 16 and the control valve of this invention designated generally by the reference numeral 18. As is customary in such devices, the main fuel cock 16 may embody thermostatic means (not shown) for controlling flow of fuel in the main fuel pipe 14 in response to the heat generated by the main burner 10. Consequently, the system of Fig. 1 is adapted for gas range application wherein the main burner 10 is located in the oven compartment.

A pilot burner 19 is provided for the main burner 10 and receives a supply of fuel from the manifold 12 through a conduit 22 which is provided with a separate pilot shut-off cock 23. In addition to thermostatic control of the main burner 10, a time control arrangement may be provided as will be hereinafter described and includes a time clock 25 having a control switch 29 associated therewith in the usual manner.

Referring now more particularly to Figs. 2 and 3 in conjunction with Fig. 1, the control device 18 comprises a valve casing 20 having an inlet 22 and an outlet 24 for connection to the main fuel pipe 14 in which the control device 18 is interposed as described. The valve casing 20 is provided with a valve seat 26 which intersects the inlet 22 and outlet 24. A control valve member 28 is movable between open and closed positions relative to the valve seat 26 for controlling the fuel supply in the main fuel pipe 14 and is biased to the closed position by a coil spring 30. The valve parts contained in the valve casing 20 may be conventional and only the essential parts will be described herein. Accordingly, a valve operating stem 32 is operatively connected with the valve member 28 and projects from the casing 20 for axial movement by means to be described.

A control casing 34 is secured to the valve casing 20 and houses the electromagnetic actuator and the automatic pilot control of this invention. Since the valve stem 32 projects into the casing 34, a compact arrangement of the parts is facilitated. The electromagnetic actuator comprises a coil member 36 which is secured to the control casing 34 by means of the screw 38. An armature 40 is cooperable with a pole face 39 projecting from the coil 36 in the usual manner and is pivoted at one end on a support 42 forming part of a frame 44 of the relay. Pivotal movement of the armature 40 to and away from the pole face 39 to establish the attracted and released positions respectively, is limited by the provision of a stop 46 which projects from the frame 44 and overlies a free end of the armature 40 for this purpose. A tension spring 48 extends between the pivoted end of the armature 40 and a spring retainer 50 on the frame 44 for biasing the armature to its released position as limited by the stop 46.

The casing 34 is provided with a cover 52 which forms a support for the automatic pilot component of this invention. Thus, a thermal element comprising a bulb 54, capillary tube 56, and expansible actuating element 58 is arranged with the bulb element 54 located to be heated by a flame from the pilot burner 19 and the expansible element 58 within the casing 34. Suitable adjusting means are provided for positioning the expansible element 58 relative to the cover 52 and take the form of a threaded bushing 60 which extends through the cover 52 and is suitably bored for the reception of the capillary tube 56 which extends therethrough. A lock-nut 62 is provided for the bushing 60 and operatively engages the cover member 52 to secure the parts in position thereon.

A lever device comprising in this embodiment a single lever arm 64 is positioned in the casing 34 for transmitting movement from the expansible member 58 and the armature 40 to the valve stem 32. One end of the lever arm 64 is provided with an aperture 66 for the reception of a reduced end 68 formed on the operating stem 32 and defining a shoulder upon which the lever arm 64 may rest. The opposite end of the lever arm 64 is also apertured for the reception of a tongue 70 formed on a tab member 71 which is secured to the armature 40 as by the rivets 72. The lever arm 64 is thus supported at opposite ends on one side thereof for operative engagement with the operating stem 32 of the valve member 28 and the tab 71 of the armature member 40.

The lever arm 64 is maintained by the arrangement described in operative engagement with a button 74 carried by the expansible member 58. The button 74 is positioned intermediate the ends of the lever arm 64 on the opposite side thereof from the operating stem 32 and the projection 71. As is customary in such devices, the expansible member 58 is movable by expansion of the fluid contained in the bulb 54 when such fluid is heated by a flame at the pilot burner 19. In this embodiment, the fluid is preferably mercury which becomes completely vaporized by the heat of the pilot flame for actuating the expansible member 58 as described.

The electrical connections for the coil 36 of the relay and the clock operator 25 will be described in connection with the operation of the apparatus which now follows:

Assuming that the bulb 54 is being heated by a flame from the pilot burner 19 and the coil 36 is deenergized as by operation of the clock 25 then the parts will be in the position shown in Figs. 1, 3 and 4. If now the switch operator 29 associated with the clock 25 closes its contacts, then a circuit is closed from line wire L¹, wire 73, coil 36, switch 29, wire 75 and line wire L². The coil 36 becomes energized and the armature member 40 will be moved to its attracted position. During such movement, the armature member 40 fulcrums about the support 42 and rotates counterclockwise until the central portion contacts the pole face 39. Since the tab 71 is moved downwardly in this operation, the bias of the valve spring 30 rotates the lever arm 64 in a clockwise direction about the button 74 as a fulcrum. The opposite or left-hand end of the lever arm 64 moves upwardly in the control casing 34 for closing movement of the valve member 28 under bias of the valve spring 30 but with snap-action. Thus, the control valve 18 shuts off the flow of fuel to the main burner 10.

When the coil 36 becomes deenergized as by opening of the control switch 29, then the armature spring 48 rotates the armature 40 clockwise about the support 42 until the left-hand end of the armature 40 contacts the stop 46. Thus, the tab 71 is moved upwardly and the tongue 70 thereon rotates the lever arm 64 counterclockwise so that the operating stem 32 is moved downwardly against the bias of the valve spring 30 also with snap-action. The valve member 28 is thus moved to open position to permit flow of fuel in the main fuel pipe 14 to the main burner 10 where it is ignited by the flame at the pilot burner 19. This completes the operation of the control valve 18 electrically by means of the relay operator.

In the event that the flame at the pilot burner 19 is extinguished, then the bulb 54 will cool and the expansible member 58 will contract. The button 74 is thus moved upwardly causing the lever arm 64 to rotate clockwise about the tongue 70 on the tab 71. The left-hand end of the lever arm 64 moves upwardly in the control casing 34 causing the valve member 28 to close under bias of the valve spring 30 with gradual action. Hence, it will be apparent that the valve member 28 will be moved to open position only if the expansible member 58 is in its expanded condition and the coil 36 of the relay operator is deenergized. Should the expansible member 58 be contracted or should the coil 36 be energized, then the valve member 28 cannot move to its open position relative to the valve seat 26.

It will further be observed that the control valve 18 is normally open insofar as the electromagnetic operator is concerned, that is, the valve member 28 is moved to open position when the coil 36 is deenergized. Thus, in the event of power failure, the appliance may be used under manual control without the necessity for special manipulation of by-pass valves or valve opening devices. The automatic pilot function obviously remains fully operative under power failure conditions. However, if desired, control valve 18 operating on a similar principle but of the normally closed type could be provided. This type of device would retain the advantages of low cost and of low pressure drop, but special provision would be required for operation of the appliance during power failures.

Fig. 4 embodiment

In the embodiment shown in Fig. 4, a control valve 79 includes the coil 36 and its armature 40 which are disposed in overlying relationship with the operating stem 32. Consequently, the expansible member 58 is also reversed relative to the operating stem 32 and a special casing 80 is employed in this embodiment to accommodate the changed arrangement of parts. Thus, the coil 36 is secured by means of a screw 38 to the upper surface of the casing 80 intermediate the operating stem 32 and the expansible member 58 which is adjustably secured to the lower wall of the casing 80 as previously indicated. A closure plate 82 is carried on the casing 80 to provide access to the interior when desired.

The lever device comprises a pair of longitudinally extending lever arms 84 and 86 respectively which are interlocked in end-to-end engagement by a tongue 88 on the lever 86 entering a suitably apertured end on the lever 84. The opposite or free end of the lever 84 is provided with an aperture 90 for the reception of a projection 92 on the end of the operating stem 32 as in the previously described embodiment, so that the lever arm 84 can rest upon the shoulder formed thereby. The opposite end of the lever arm 86 is pivotally mounted and, to this end, is received within an aperture 94 formed in the casing 80. Intermediate the pivot 94 and the tongue 88 the lever arm 86 is suitably apertured to receive the button 74 as in the previously described embodiment.

The armature member 40 carries a tab 96 which is secured as by the rivets 98 to the armature member 40 but is of slightly different conformation than the previously described embodiment. Thus, the terminal end of the tab 96 is provided with a tongue 100 which is received within an aperture 102 formed intermediate the ends of the lever arm 84. Hence, the armature member 40 operatively engages the device on the opposite side thereof from the operating stem 32 and the expansible member 58.

Operation of the Fig. 4 embodiment

The control valve 79 can be substituted in the installation of Fig. 1. The electrical operation of the valve member 28 is obtained by means of the energization of the coil 36 and the automatic pilot control of the valve member 28 is obtained by means of the flame sensitive thermal element to which the expansible member 58 is connected. If the expansible member 58 is in its expanded condition and if the coil 36 is deenergized, then the valve member 28 is in the open position as shown in Fig. 1. When the coil 36 is energized, either by means of a clock operator 25 or a thermostat 76, then the armature 40 is attracted to the pole face 39. In such operation, the armature member 40 fulcrums about the support 42 and rotates in a clockwise direction until the central portion contacts the pole face 39. The tab 96 moves as a unit with the armature 40 and the valve spring 30 rotates the lever arm 84 in a clockwise direction about the tongue connection 88 as a fulcrum. Consequently, the operating stem 32 moves upwardly under bias of the valve spring 30 allowing the valve member 28 to move to its closed position with snap-action and shut off flow of fuel in the main fuel pipe 14.

Upon deenergization of the coil 36 of the electromagnetic operator, then the armature spring 48 rotates the armature member 40 in a counterclockwise direction about the support 42 until

the left-hand end strikes the stop 46. Thus, the tongue 100 on the tab 96 is moved downwardly for rotating the lever arm 84 in a counterclockwise direction about the connection 88 and forcing the operating stem 32 downwardly for opening the valve member 28 also with snap-action. This completes the operation of the valve electrically by means of the electromagnetic operator.

In the event that the flame at the pilot burner 19 is extinguished, then the expansible element 58 contracts and the button 74 will move downwardly relative to the casing 80. The lever arm 86 is rotated counterclockwise by the operating stem 32 under bias of the valve spring 30 about the wall of the aperture 94 as a fulcrum. The lever 84, at the same time, is rotated clockwise about the wall of the aperture 102 for closing the valve member 28 with gradual action. As in the previous embodiment, it is only if the expansible member 58 is expended and the coil 36 deenergized, that the valve member 28 may be moved to open position. If the expansible member 58 is contracted, or if the coil 36 is energized, then the valve member 28 will be moved to the closed position under bias of the valve spring 30.

Fig. 5 embodiment

In this embodiment of the invention, a control valve 103 includes a snap-action movement of the valve member 28 under automatic pilot control in place of the gradual action of the previously described embodiments. The arrangement of the parts is similar to that shown in Figs. 1 to 3 inclusive in that the expansible member 58 is positioned in overlying relation to the operating stem 32 while the coil 36 and its armature 40 are in side-by-side relation with the operating stem 32. Moreover, the armature spring 48 is now positioned in reverse relation to the coil 36 thus permitting use of the tab 96 and tongue 100 as in Fig. 4 embodiment. Such arrangement of the tab 96 provides for greater length of the lever device comprising a single lever arm 104 in this embodiment. Thus, the lever arm 104 is supported at opposite ends on the operating stem 32 and the tab 96 respectively as described in connection with the Figs. 1 to 3 embodiments and further description is deemed unnecessary.

The snap-action means of this embodiment takes the form of an operating lever 106 which is mounted at one end on the button 74 and at the opposite end on a support 108 secured as by the rivets 110 to the cover 52. A conventional thrust element 112 having an annular knife edge 114 is cooperable with a clicker disc 116 which, in turn, is supported on a knife-edge mounting 118 formed on a housing 120. The clicker disc 116 operatively engages with a plunger 122, the opposite end of which operatively engages with the lever 104 intermediate its ends. Upon sufficient thrust being applied by the thrust member 112, the clicker disc 116 will reverse its position and operate the plunger 122 for rotating the lever 104 as will be apparent.

Operation of Fig. 5 embodiment

The control valve 103 can be substituted in the installation of Fig. 1. As in the previously described embodiments, the electrical operation of the valve member 28 is obtained by means of the coil 36 moving the armature member 40 between attracted and released positions. The automatic pilot control is obtained by means of the expansible member 58 moving between expanded and

contracted positions. As shown in Fig. 5, the expandible member 58 is expanded and the coil 36 is deenergized so that the valve member 28 is in the open position. When the coil 36 is energized then the armature 40 is attracted to the pole face 39 and fulcrums about the support 42. This movement of the armature 40 is in a clockwise direction so that the bias of the valve spring 30 rotates the lever arm 104 also in a clockwise direction about the plunger 122 as a fulcrum. Since the armature member 40 is always moved with snap-action toward the pole faces 39, then the operating stem 32 will move upwardly serving to close the valve member 28 under bias of the valve spring 30 with snap-action as in the previously described embodiments.

If the coil 36 is now deenergized the armature spring 48 rotates the armature 40 in a counterclockwise direction about the support 42 until the right-hand end of the armature 40 strikes the stop 46. Thus, the tongue 100 on the armature tab 96 is moved upwardly and the lever arm 104 is rotated in a counterclockwise direction about the plunger 122 as a fulcrum. The opposite end of the lever arm 104 consequently forces the operating stem 32 downwardly and serves to open the valve member 28 against the bias of the valve spring 30 with snap-action.

In the event that flame of the pilot burner is extinguished, then the expandible member 58 contracts moving the button 74 upwardly. The left-hand end of the operating lever 106 follows the movement of the button 74 and the lever rotates clockwise about the support 108 due to bias of the clicker disc 116 which thereupon reverses its position from that shown in Fig. 5 after the thrust of the thrust element 112 has been sufficiently relieved. Consequently, the plunger 122 moves upwardly due to the bias of the operating stem 32 on the lever device 104 and the valve member 28 moves to closed position with snap-action.

It will be apparent that expansion of the expandible member 58 will serve to conduct a reverse operation of the operating lever 106 and the snap-action mechanism associated therewith so that the valve member 28 is moved to open position against the bias of the spring 30 also with a snap-action. As in the previously described embodiments, the valve member 28 will be opened only if the expandible member 58 is expanded and the coil 36 is deenergized. In the event that the expandible member 58 is contracted, or if the coil 36 is energized, then the valve member 28 will consequently be closed.

While several embodiments of the invention have been disclosed herein it will be apparent that many other changes may be made in the details of construction and arrangement of parts without departing from the scope of the invention as defined in the appended claims.

I claim:

1. Control apparatus comprising in combination, a control valve casing having inlet and outlet passages and a valve seat, a valve member movable between open and closed positions relative to said seat for controlling flow through said valve passages, said valve member being biased to said closed position, an operating stem for said valve member and projecting from said casing, an expandible member positioned on one side of said valve stem for movement substantially parallel thereto, electromagnetic means having an electromagnet and an armature movable between attracted and released positions in response to

energization and deenergization of said electromagnet, means for biasing said armature to said released position, a lever device including a pivot movable with said armature and a lever mounted on said pivot, said lever being operatively connected to said valve stem and to said expandible member for moving said valve member against its bias to said open position thereof upon expansion of said expandible member while said armature is in said released position, said pivot being movable to an inactive position relative to said lever when said armature is moved to said attracted position to render said lever ineffective to hold said valve member in said open position.

2. Control apparatus as claimed in claim 1 wherein said lever device includes a single lever arm having its opposite ends on one side thereof in operative engagement with said valve stem and said pivot respectively, said expandible member being positioned intermediate said ends and being operatively engageable with an opposite side of said lever arm.

3. Control apparatus comprising in combination, a control valve casing having inlet and outlet passages and a valve seat, a valve member movable between open and closed positions relative to said seat for controlling flow through said valve passages, said valve member being biased to said closed position, an operating stem for said valve member and projecting from said casing, an expandible member positioned on one side of said valve stem for movement substantially parallel thereto, electromagnetic means having an electromagnet and an armature movable between attracted and released positions in response to energization and deenergization of said electromagnet, means for biasing said armature to said released position, a lever device including a pair of longitudinally extending lever arms interlocked in end-to-end engagement and having the opposite ends thereof in operative engagement with said valve stem and said expandible member respectively, and pivot means movable with said armature and operatively engaging one of said lever arms adjacent said interlocked ends, said pivot means being movable to an inactive position relative to said one lever arm when said armature is moved to said attracted position to render said one lever arm ineffective to hold said valve member in said open position.

4. Control apparatus comprising in combination, a control valve casing having inlet and outlet passages and a valve seat, a valve member movable between open and closed positions relative to said seat for controlling flow through said valve passages, said valve member being biased to said closed position, an operating stem for said valve member and projecting from said casing, an expandible member positioned on one side of said valve stem for movement substantially parallel thereto, electromagnetic means having an electromagnet and an armature movable between attracted and released positions in response to energization and deenergization of said electromagnet, means for biasing said armature to said released position, pivot means on said armature, a lever device including a lever arm having its opposite ends on one side thereof in operative engagement with said valve stem and said pivot means respectively, and a second lever arm operatively engageable with the median portion of the first said lever arm and said expandible member for moving said valve member against its bias to said open position thereof while said armature is in said released position, said pivot means

being movable to an inactive position relative to said first lever when said armature is moved to said attracted position to render said first lever arm ineffective to hold said valve member in said open position.

5. Control apparatus as claimed in claim 4 wherein snap-action means are interposed between said second lever arm and said first lever arm for imparting snap-action movement to said valve member upon movement of said expandible member.

6. Control apparatus comprising in combination, a control valve casing having inlet and outlet passages and a valve seat, a valve member movable between open and closed positions relative to said seat for controlling flow through said valve passages, said valve member being biased to one of said positions, an operating stem for said valve member and projecting from said casting, an expandible member positioned on one side of said valve stem for movement substantially parallel thereto, a lever member operatively connected to said expandible member to be adjustable bodily thereby between active and inactive positions in response to expansion and contraction respectively of said expandible member, said lever member being operatively connected to said operating stem for actuating said valve member in said active position of said lever member, an elec-

10
